UNITED STATES PATENT OFFICE

HENRY W. ROOS, OF CINCINNATI, OHIO

ADJUSTABLE SHORE

Application filed March 13, 1930. Serial No. 435,450.

This invention relates to apparatus for forming concrete floor molds, and particularly to temporary supports or shores on which the molds are supported.

It is frequently desirable to construct one portion of a floor of a thicker slab of concrete than another portion where the thick portion is required to carry a heavier load than the other part. The forms for the mold for the thick slab are assembled in a lower plane than those for the thin slab, with a substantially vertical wall between them, the difference in thickness between the two slabs being varied according to the difference in the loads to be carried thereon.

The principal object of this invention is the provision of a shore which is simple in construction, efficient in use, and adapted to support the floor forms on one side at a higher level than those on the other side.

Another object of the invention is the provision of a shore of this kind adapted to support the floor forms on one side in a higher plane than those on the other side, said shore being adjustable to vary the vertical distance between said planes.

Still another object of the invention is the provision of a shore adapted to support a plurality of floor forms at their corners, said shore being adjustable to support one of said forms in a different horizontal plane than the others.

To these and other ends, the invention consists in the construction and arrangement of parts that will appear from the following description when read in conjunction with the accompanying drawings, the novel features being pointed out in the claims following the specification.

In the drawings:

Fig. 1 is a fragmentary plan view of a floor mold illustrating one embodiment of the invention;

Fig. 2 is a fragmentary vertical section of the same, taken substantially on line 2-2 of

Fig. 1, and looking in the direction of the arrows at said line;

Fig. 3 is a section on line 3-3 of Fig. 4, looking in the direction of the arrow at said line and showing one of the floor forms detached;

Fig. 4 is a side elevation of the parts shown in Fig. 2;

Fig. 5 is an elevation of the other side of the shore shown in Fig. 4;

Fig. 6 is a perspective view of an adjustable carrier shown in Fig. 4;

Fig. 7 is a perspective view of another shore shown in Fig. 1;

Fig. 8 is a plan view of the same;

Fig. 9 is a perspective view of a carrier shown in Fig. 8;

Fig. 10 is a front elevation of a slightly modified form of the shore shown in Fig. 4;

Fig. 11 is a side elevation of the same;

Fig. 12 is a plan view of the same showing a fragment of a floor form supported thereon and another detached therefrom, and

Fig. 13 is a section taken on line 12-12 of Fig. 11 and looking in the direction of the arrows at said line.

Referring specifically to the drawings, in which like reference numerals refer to the same parts in the several views, 1 represents a floor form of well known type. The forms 1 are substantially rectangular or square in form, and are cut away at their corners to fit around the tops of shores 2, 3 and 4 on which they are supported to form a floor mold.

In the embodiment illustrated, the forms 1' are assembled in a lower plane than the forms 1'' for the purpose of forming a thicker slab thereon. Four of the forms 1 are shown supported on each of the shores 2, 3 and 4, those supported on the shores 2 all being in the same plane, while two of those supported on the shore 3 are supported at a lower plane than the other two, and one of those supported on the shore 4 is supported at a lower plane than the other three. The

AUTOMATICALLY EXTENSIBLE AND COLLAPSIBLE TRAY

Filed Jan. 7, 1931

2 Sheets-Sheet 2

UNITED STATES PATENT OFFICE

KARL OSTEN SCHAUMAN, OF HAMPTON WICK, ENGLAND

AUTOMATICALLY EXTENSIBLE AND COLLAPSIBLE TRAY

Application filed January 7, 1931, Serial No. 507,204, and in Great Britain September 15, 1930.

The invention refers to a tray for carrying dishes, crockery and the like, which tray can be equipped, merely by the momentary suspension of normally prevailing spring or other tension, with a stand of its own, thus forming a convenient emergency table. For this purpose I construct the tray as a shallow casing, the underpart of which is housing the telescopic legs, the means for sliding and pivoting the latter and the means for keeping the same either in the folded or in the partly or fully extended positions, ready for use in either.

An example of a simple way of carrying out the invention is described and illustrated in the annexed drawings of which

Fig. 1 is a perspective view of the tray,
Fig. 2 is a perspective view of the tray extended,

Fig. 3 is an underplan of table folded,
Fig. 4 is a section on line 4—4 of Fig. 3,

Fig. 5 is a section similar to 4 with the legs beginning to descend,

Fig. 6 is a section of tray and table fully opened.

The tray-top *a* is bordered by downwardly depending rims *a*¹, thus providing a hollow space on the underside of the tray. Arranged at each corner of the tray and within the rim *a*¹ are metal or like brackets *b* which are spaced away from the rim *a*¹ as shown in Fig. 3 and are provided with key-hole slots *b*¹ (see Fig. 4.) Arranged transversely across the ends of the tray are pivot spindles *c* the ends of which are located in the slots *b*¹, suitable rollers or the like *c*¹ being provided. The spindles *c* carry at or near their centers hand-loops *c*² and the rim *a*¹ of the tray is cut away at its ends as at *a*² in order that the hands may be readily placed under the tray to grip the hand-loops *c*². By means of the hand-loops *c*² the spindles *c* can be caused to recede from one another along the slots *b*¹ against the action of tension springs *h* which are arranged one along each long side of the tray and which are secured at their ends to the ends of the spindles *c* (see Fig. 4). The center points of the tension springs *h* are secured as at *k* to the sides of the tray.

Freely pivoted to the ends of the spindles *c* are cranked arms *d*¹ secured to the ends of tubes *d* which form the upper parts of the legs when the tray is converted into a table. The cranked arms *d*¹ are of the shape shown clearly in Fig. 6 for a purpose hereinafter described.

The tubes *d* are telescopically arranged within further tubes *e* which are pivoted as at *e*¹ at their upper ends to the down-turned ends of brackets *f* mounted along the sides of an undershelf *g*. Means are provided to prevent the complete withdrawal of the tubes *d* from the tubes *e*, said means comprising a length of wire *l* which is secured at its lower end to a pin *e*² near the lower end of the tube *e* and at its upper end is provided with a head *l*¹ arranged within the tube *d*, this head *l*¹ in conjunction with the inturned end *d*² of the tube *d* serving the purpose above referred to.

The parts of the device are arranged and operated in the following manner: as a tray, the undershelf *g* is accommodated in the hollow recess on the underside of the tray top *a* and in close proximity to the same (see Fig. 4 which shows the device in use as a tray). The tubes *d* are telescoped within the tubes *e* and the tubes *e* are arranged horizontally under the shelf *g*. It will be seen that in this position the connection between the cranked arms *d*¹ and the spindles *c* are arranged inside the pivot connections *e*¹ of the tubes *e* to the brackets *f* carried by the shelf. The pull of the springs *h* therefore serves to keep the collapsed legs *d*, *e* raised and also enables a neat and compact tray to be provided. As will be appreciated on reference to Fig. 3, the two sets of tubes *e* fold up side by side.

When it is desired to convert the tray as shown in Fig. 1 into a table the hands are placed under the rim *a*¹ and the hand-loops *c*² are gripped. The hand-loops *c*² are then pulled and this as explained above will cause the spindles *c*¹ to recede from one another against the action of the springs *h*. Movement of the spindles *c* will cause the pivot point between the spindles *c* and the cranked arms *d*¹ to pass finally underneath and be-

yond the pivot point e^1 ; it will also cause the tubes d to be slightly withdrawn from the tubes e (see Fig. 5). As soon as the handles have been pulled sufficiently to bring the ends of the arms beyond the pivot points e^1 the tubes e will commence to fall about the pivot e^1 due to their own weight since the springs h no longer maintain the same in the raised position. They will then fall until they reach a substantially vertical position, the cranked arms d^1 meanwhile pivoting on the spindles c and the weight of the shelf g and tubes e will cause these parts to slide out of the tubes d . At the end of this movement the tray a will be arranged above four substantially vertical legs with an intermediate shelf. The hand loops c^2 should now be released whereupon the springs h will again come into action to draw the upper ends of the tubes d together. This drawing together of the upper ends of the tubes d will cause the legs d and e to slope outwardly as shown in Fig. 6 whereupon the tray a which now forms the table top will be firmly supported. The tubes d just above the upper ends of the tubes e are arranged to bite into recesses in the brackets f to give a good grip and a firm stand.

Of course by releasing the hand-loops c^2 before the legs d, e are fully extended, the height of the tray a may be adjusted to suit individual requirements.

In order to collapse the table and to reconvert the same into a tray, it is merely necessary to place the hands under the rim and to pull the hand-loops c^2 . This it will be appreciated will cause the legs to become vertically disposed, when, with the hand-loops c^2 still pulled apart, the tubes d can be telescoped into the tubes e by pressure on the tray a . When the tubes d have been fully telescoped into the tubes e so that the shelf g is arranged in close proximity with the underside of the tray top, the handles c^2 may be released when the springs h will act to swing the tubes e up under the tray top and to maintain the same in the raised position as shown in Fig. 4 and as described above.

It will be understood that the return of the spring-tension at any moment during extending or folding fixes the parts in the position momentarily attained or in other words, only if the hands are pulling asunder can the further opening or closing be proceeded with, which of course permits of the handiest adjustment imaginable.

Although the example described mentions spring-tension only, I may use other forms of controlling the action and maintaining the parts in their desired positions without deviating from the invention.

What I claim as my invention and desire to secure by Letters Patent is:—

1. A combined serving tray and table comprising a tray element, a pair of rods extend-

ing transversely across the tray at the under side and near the ends thereof and connected with the tray for inward and outward movement relative to each other, yieldable means tending constantly to move said rods relatively inward, a plurality of legs one at each end of each rod, said legs being pivoted at their upper ends to said rods for movement between folded positions underlying the tray element and extended tray element supporting positions, members slidably mounted on said legs, and a leg spreader element pivotally connected with said members, whereby the spreader element is movable upwardly along the legs to lie closely adjacent to the tray element when the legs are folded, and downwardly along said legs when the same are extended to hold the lower end portions of the legs against both inward and outward movement relative to each other.

2. A combined serving tray and table as set forth in claim 1 in which the legs comprise upper and lower telescopic sections and in which the spreader element is pivotally connected to the upper ends of the lower leg sections.

3. A combined serving tray and table as set forth in claim 1 in which the pivotal connections between the legs and the rods are located at the free ends of angle members which extend first laterally from the upper ends of the legs and then downwardly in spaced relation to the legs to permit the members to which the spreader element is pivoted to be moved across the rods to dispose the pivots between the spreader element and said members above and outwardly relative to the rods when the legs are folded, whereby the yieldable connections between the rods serve to hold the legs against swinging to extended positions when the legs are folded.

KARL OSTEN SCHAUER.
